UNITED STATES PATENT OFFICE

170,972

WHEEL TRIM HUBCAP

James K. Gaylord, Chicago, Ill., assignor to Gaylord Products, Incorporated, Chicago, Ill., a corporation of Delaware

Application April 1, 1953, Serial No. 24,295

Term of patent 14 years

(Cl. D14—30)

To all whom it may concern:

Be it known, that I, James K. Gaylord, a citizen of the United States, residing at Chicago, in the county of Cook and State of Illinois, have invented a new, original, and ornamental Design for a Wheel Trim Hub Cap, of which the following is a specification, reference being had to the accompanying drawing, forming part thereof.

Fig. 1 is a front elevational view of a wheel trim hub cap showing my new design;

Fig. 2 is a side elevational view of same;

Fig. 3 is a sectional view taken along the line 3—3 of Fig. 1; and

Fig. 4 is a sectional view taken along the line 4—4 of Fig. 1.

I claim:

The ornamental design for a wheel trim hub cap, substantially as shown,

JAMES K. GAYLORD.
